GAME SCORING DEVICE

Edward E. Stevenson, Whittier, Calif.

Application October 20, 1947, Serial No. 780,899

16 Claims. (Cl. 235—90)

1

This invention has to do generally with scoring devices, and is more particularly concerned with devices whereby a game-score may be kept by advancing counters over a scoring board.

While the invention is adapted for use in connection with any such devices, it is particularly applicable to devices whereby the score is "pegged" by advancing pegs along rows of sockets which represent count-values. A cribbage board is a typical example of such a device and I will therefore confine my description to such an embodiment of my invention, but it is to be understood this is in no way to be considered as limitative on the broader aspects of the invention nor on the broader claims appended hereto.

Typically, a cribbage board has, for each player, a series of sockets which, in total number or in an even multiple of the total number, represent the "going out" score. Each player uses a pair of pegs, the most advanced peg representing his score at the end of the last hand. When the next hand is played and counted, the scorer withdraws the rearward peg from the board, counts off the score of the hand in terms of sockets beyond the forward or advanced peg, and inserts the withdrawn peg in the last socket of the count. The sockets are not usually individually numbered and it is customary for the player to "tick" off the sockets, one by one, as he is adding the hand-score to the last total. This not only becomes tiresome but it often leads to errors in the pegged scoring.

It is therefore among the objects of my invention to provide a scoring device whereby the one-by-one counting of sockets is unnecessary and whereby, to score a hand, it is only necessary to remove the rearward peg and then replace it opposite a number which corresponds to the count of that particular hand.

How this is accomplished will be better understood from consideration of the following detailed description of preferred embodiments of my invention, reference being made to the accompanying drawings, in which:

Fig. 1 is a top plan view of one embodiment of my invention.

Fig. 2 is a view similar to Fig. 1, but showing the scoring elements moved to advanced positions;

Fig. 3 is a plan view of the device with the cover plate removed, or may be considered as a section on line 3—3 of Fig. 4, though rotated 45° with relation thereto;

Fig. 4 is a section on line 4—4 of Fig. 3;

2

Fig. 5 is a broken-away perspective view of one of the actuating gear segments;

Fig. 6 is a detail section on line 6—6 of Fig. 3;

Fig. 7 is a view similar to Fig. 5 but showing the other of the actuating gear segments;

Fig. 8 is a detached, top plan view of a partition plate;

Fig. 9 is a broken-away section on line 9—9 of Fig. 1;

Fig. 10 is a section on line 10—10 of Fig. 9;

Fig. 11 is a broken-away section on line 11—11 of Fig. 4;

Fig. 11a is a broken-away section on line 11a—11a of Fig. 3;

Fig. 12 is a top plan view of a variational embodiment of the invention;

Fig. 13 is an enlarged section on lines 13—13 of Fig. 12; or it may be considered as a section on line 13—13 of Fig. 14;

Fig. 14 is a section on line 14—14 of Fig. 13;

Fig. 15 is a reduced section on line 15—15 of Fig. 13;

Fig. 16 is a view similar to Fig. 14, but on a scale reduced therefrom and showing certain parts in different relative positions; and

Figs. 17 is a view similar to Fig. 16, but showing the relative positions of parts when the board is being cleared of a previous score.

In the embodiment of the invention illustrated

in Figs. 1 to 11a, inclusive, the scoring device is in the general form of a square box 30 made up of a base member 31 and a scoring or pegging board 32, the marginal flanges 33 and 34 of members 31 and 32, respectively, opposing each other and taking between them a partition plate 35 (Figs. 4, 6 and 8). The base, board and partition are detachably held in assembly by corner screws 36 (Fig. 6) which extend through bosses 37, 38, and by pilot pins 39 which extend through bosses 40, 41 (Fig. 4).

As will later appear, indicia carried by certain elements within box 30 are to be visible through board 32 and therefore portions, at least, of said board are to be cut away or are to be transparent.

For instance and as illustrated, the entire board 32 may be fabricated of a transparent, plastic material; it being a matter of choice whether such portions of the board as may not need to be transparent be surfaced or sandblasted to leave "windows" through which only the indicia are visible.

Board 32 is pierced to provide two circularly arranged series 42 and 43 of pegging holes or sockets, both series being centered on the axis

55 A of the board. Generally these holes or sockets

may be considered as representing "scoring positions." In the particular embodiment here shown, the holes of each series are sixty in number (though this particular number is not to be considered as limitative) series 42 and 43 being made up, respectively, of sockets 44 and 45. The sockets of each series are equiangularly spaced apart and preferably, any given socket of one series is in radial alinement with a companion socket of the other series. At opposite sides of a selected pair of radially alined sockets, board 32 is marked with arrows B to establish the starting positions of certain scoring pegs, as will later be described.

Mounted within box 10 for independent rotation about axis A, are counting wheels 46 and 47, wheel 47 being in the form of a disk having a depending hub 48 (Figs. 4 and 11) while wheel 46 is cup-shaped, having an integral, central pinion 49 extending downwardly from cup-bottom 50, and having a horizontal, annular flange 51 at its upper edge.

The counting wheels are mounted as follows. A shaft 58, carrying an integral pinion 59 which is of the same diameter and pitch as pinion 49, is journaled at 60 and 61 in base 31 and board 32, respectively. Pinion 49 and its wheel 46 are supported by shaft 58 and pinion 59 but are rotatable with respect thereto. Washer 62 is interposed between cup-bottom 50 and hub 48, bringing disk 47 into the plane of flange 51. Pin 63, carried by shaft 58 and seated in hub-notch 64 (Figs. 4 and 11) keys wheel 47 to shaft 58. Accordingly, rotation of pinion 59 causes coincident rotation of wheel 47, while rotation of pinion 49 causes coincident rotation of wheel 46. However, rotation of one wheel does not in any way affect the other wheel.

Printed on flange 51 and around the edge of disk 47, respectively, are the count-indicia generally indicated at 65 and 66, which, in this embodiment of the invention, consist of arcuately arranged series, both centered on axis A, of numbers having progressively increasing value. For instance, each of the illustrated series starts with zero and progresses, by "ones," to 29 which latter is the maximum score to be made in a single hand of cribbage. Wheels 46 and 47 may thus be considered as counters or number-carrying members. The numbers are equiangularly spaced and, when a given number of either wheel is lined up with a given socket 44 or 45, all other numbers of that wheel are in radial alinement with corresponding sockets.

Lugs or abutment formations 67 and 68 (Fig. 10) extend radially from flange 51 and disk 47, respectively, at points in radial alinement with the zero marks of the associated wheels.

The count-indicia 65 and 66 are visible through the transparent board 32 and, in scoring, indicia 65 are associated with socket-series 42, and indicia 66 are associated with socket-series 43. It will be seen that rotation of a given wheel causes the indicia or number-series of that wheel to traverse the associated socket-series.

I will now describe the means for powering the number wheels whereby, during scoring, they are adapted to be rotated in the direction in which their number-series progress in value, namely, in a clockwise direction, as viewed in Figs. 1, 2 and 3.

Referring particularly to Figs. 3, 4, 5 and 7, I have provided a pair of actuating gear segments 70 and 71 mounted for individual oscillation on diametrically opposite corner posts or pilot pins 39. Segment 70 meshes with upper pinion 49 and

thus becomes the actuator for counter wheel 46. Segment 71 is similar to segment 70 except that it is bent downwardly at 72 to bring its teeth into the plane of lower pinion 59, with which said teeth mesh. Thus, segment 71 is adapted to serve as the actuator for counter wheel 47.

Segment 70 rides on the associated hub 49 and the arcuate track 73 and is held from upward displacement by partition plate 35, the upstanding lugs 74 and 75 limiting the extent of segment-oscillation about post 39. Similarly, segment 71 rides on the associated hub 49 and the arcuate track 76 and is held from upward displacement by the arcuate rib 77 pressed downwardly from plate 35 (Figs. 4 and 8) the upstanding lugs 78 and 79 limiting the extent of segment-oscillation.

Segments 70 and 71 have arcuate tongues 80 and 81, respectively, which extend through slots 82 in base-flange 33 and terminate, exteriorly of box 30, in down-turned flanges 83 (Figs. 3 and 11a). Springs 84 are applied to diagonally opposite bosses 37 and engage, one each, the shoulders 85 provided, one each, on segments 70 and 71, the mid-portions of the springs engaging the flange 33.

Springs 84 are pre-stressed and arranged in such a manner that they tend to rotate segments 70 and 71 individually in a counter-clockwise direction, as viewed in Figs. 3, 5 and 7, thus acting through pinions 49 and 59, respectively, in a manner tending individually to rotate wheels 46 and 47 in a clockwise direction, as viewed in Figs. 1, 2 and 10.

Assuming a complete game has been scored and it is desired to prepare the device for the scoring of a new game, the board is first "cleared" by withdrawing all scoring pegs from sockets 44 and 45. Springs 84 urge segments 70 and 71 to the positions of Figs. 5 and 7, respectively, the stop shoulders 74 and 78 establishing these positions.

The device is then "restored" and "wound" by thrusting the tongues 80, 81 inwardly, through manual pressure exerted on flanges 83, which action individually rotates segments 70, 71 in a clockwise direction, as viewed in Figs. 5 and 7, to the positions of Fig. 3. Such segment movement rotates wheels 46 and 47 in a counterclockwise direction as viewed in Figs. 1, 2 or 10. Stop shoulders 75 and 79 limit the extent of clockwise movement of segments 70 and 71 and the number series on the wheels are so located that, when the segments are at these limits, the zero markings are either in radial alinement with markings B (Fig. 1) or, preferably, slightly removed from those markings in a counterclockwise direction. Though this is not limitative, in the illustrated embodiment of the invention each segment is effective, in its movement from one limit-stop to the other, to rotate its pinion and hence the associated number wheel, through a little more than 720 degrees.

While inward pressure is maintained on flanges 83, the players insert pegs 85 and 86 (Figs. 1 and 10) in the particular sockets 44a and 45a which are in radial alinement with starting marks B. The pegs may be of any suitable shape, but preferably each has an enlarged handle portion 90 and a reduced-diameter pin portion 91, the latter having slip-fit in the board-sockets. The intermediate shoulder 92 on each pin, by contact with the upper face of board 32, serves to establish the limit to which the pin portions may be thrust. The pin portions of pegs 85 and 86 extend across the paths of formations 67 and 68, respectively, as the latter travel during wheel-rotation.

As soon as pegs 85 and 86 are socketed, pressure on flanges 83 is relieved. If the zero marks on the wheels were lined up with sockets 44a and 45a at the time of peg-entry, formations 67 and 68 are in contact with pegs 85 and 86, respectively, and consequently, there will be no wheel movement. But if the zero marks were slightly displaced in a counterclockwise direction from said sockets when the pegs were socketed, relief of pressure on flanges 83 frees springs 84 to rotate segments 70, 71 in a counter-clockwise direction, thus, through pinions 49 and 59, rotating wheels 46 and 47 in a clockwise direction until formations 67 and 68 engage pegs 85 and 86, respectively, the wheels then coming to rest with their zero markings in radial alinement with starting marks B. Of course, the clearing and restoring of one wheel may be accomplished entirely independently of the clearing and restoring of the other wheel.

The board is now in a condition to allow the scoring of a new game. Assume that a player, whose score is represented by the position of the pegs in series 42, makes three points in the first hand. He merely inserts his second peg (87) in the particular socket 44 which is radially alined with numeral "3" on wheel 46, which numeral is visible through transparent board 32. Assuming the other player makes five points in the first hand, he merely inserts his second peg (88) in the particular socket 45 which is radially alined with numeral "5" on wheel 47. The board is now in the condition of Fig. 1, and shows the score to be "three to five." At this stage of the scoring, pegs 85 and 87, respectively, may be considered the "rearward" and "advanced" pegs of the first player. Similarly, pegs 86 and 88, respectively, may be considered the "rearward" and "advanced" pegs of the second player.

Now assume the first player makes eight points on the second hand. He withdraws "rearward" peg 85 from socket 44a, thus clearing the pin portion of that peg from the path of formation 67 on wheel 46. The spring 84 associated with segment 70 immediately acts to rotate that segment in a counter-clockwise direction, as viewed in Fig. 3, and, through pinion 49, to rotate wheel 46 in a clockwise direction, as viewed in Fig. 1, until formation 67 strikes "advanced" peg 87, whereupon the wheel comes to rest with the zero marking on that wheel in radial alinement with peg 87. The player then merely places his peg 85 in the particular socket 44 which is in alinement with numeral "8" on wheel 46. Peg 85 now becomes the "advanced" peg, while peg 87 becomes the "rearward" peg (see Fig. 2).

Similarly, assuming the second player makes sixteen points on the second hand, the rearward peg 86 is first removed, whereupon segment 71 is spring-biased in a manner to rotate wheel 47 in a clockwise direction until it is stopped by the contact of formation 68 with peg 88. The second player then inserts peg 86 in the particular socket 45 in alinement with the numeral which indicates position 16 on wheel 47 (see Fig. 2). In the illustrated embodiment, this position is indicated by the digit 6 which first follows the numeral 10, but, of course, all numerals higher in value than 10 may be printed out in full if desired. Peg 86 is now an "advanced" peg, and peg 88 is a "rearward" peg.

The board is now in the condition of Fig. 2, and it shows that, in the last hand scored, the first player scored eight points and the second player scored sixteen points, this reading being

entirely independent of the scores made in the preceding hand. Of course, the relative total scores at this stage of the game may be ascertained by noting the relative positions of the two advanced pegs 85 and 86. The total score of an individual player at any stage of the game may be quickly ascertained by counting the number of sockets from starting mark B to the rearward peg and adding to that count the value indicated by the advanced peg.

It has not been found necessary to indicate progressive values for the sockets of series 42 and 43 whereby "intermediate" totals may be read directly, since, at an intermediate point in the game, the main interest is in relative standings. However, the marking of such progressive values on the board adjacent the socket-series is not to be considered as precluded by the absence of a showing thereof. Since the winning score of cribbage (120 points) is an even multiple of the number (sixty) of sockets in each series, the starting marks B indicate the "go-out" point when they are reached or passed at the end of the second revolution of an associated wheel, and therefore it is unnecessary otherwise to mark the winning point—that is, the socket which, when reached or passed by an "advanced" peg, indicates that the game is over.

As play progresses, the scoring operations described above are repeated, the pegs of a given socket-series being alternately advanced and the wheel-number alined with the "advanced" peg indicating the score of the last hand. As wheels 46 and 47 are thus independently advanced, segments 70 and 71 intermittently move in counter-clockwise direction, as viewed in Fig. 3, tongues 80 and 81 gradually approaching the dotted line positions of Fig. 3 or the full line positions of Figs. 5 and 7.

As stated above, springs 84 are adapted, through segments 70, 71, to give a little more than two revolutions to their associated pinions and number wheels, it following that the winning score of "120" may be pegged out. A player may judge whether or not he is working on his first or second series of sixty points, by observing the extent to which the finger 80 or 81 of his number-wheel-segment projects beyond the side of box 30, or if desired, the fingers may be marked as at C, (Figs. 3, 5 and 7) this marking being so located that it appears exteriorly of the box just after one revolution of the associated number wheel has been completed. However, most players need no such "half-way" mark, as they constantly have in mind whether they are in the first or second half of the game score.

Upon completion of a game, the board is "cleared" by removing all pegs, and is then "restored" to operative starting condition by thrusting flanges 80 and 81 inwardly and inserting pegs 85 and 86 in sockets 44a and 45a, respectively, all as previously described.

In Figs. 12 to 17, inclusive, I have illustrated a variational embodiment of my invention, wherein many of the principles of operation are the same as those of the mechanism just described, though, in certain regards, the particular means incorporating certain of those principles differ in detail.

Such elements as correspond exactly to given elements of the first-described embodiment, carry the same reference numerals, while such elements as are similar to, but differ in detail from given elements of the first embodiment, are given the same reference numerals with sub-script "a."

Box 30a is cylindrical in shape and the transparent, circular board 32a is secured by screws 36a directly to the annular flange 33a of base 31a. The socket series 42 and 43 are the same as in the previously described embodiment and are similarly centered about axis A.

The cross-sectional shapes and the mounting of number-carrying or counter wheels 46a and 47a are somewhat different than the shapes and mounting of wheels 46 and 47. Wheel 47a is here of cup-shape, the annular wall 100 extending upwardly from bottom wall 101 and carrying abutment 68a. The horizontal, annular flange 102 carries count indicia 66.

The flange 51 of wheel 46a carries abutment 67 and count indicia 65, but its wall 50a is centrally depressed to provide a bottom wall 103 and an annular wall 104, the latter preferably, though not necessarily, directly underlying wall 100 of wheel 47a, for a reason later to be made apparent.

Centered on axis A is an elongated pinion 105 having integral shaft-extensions 106 and 107. Extension 106 has rotational bearing in board 32a, while extension 107 has rotational bearing in plate 108 and base 31a, the plate being centrally located on and secured to base 31a by screws 109 (see Figs. 13 and 15). The opposite ends of the pinion teeth oppose board 32 and plate 108, the pinion thereby being held against excessive vertical displacement. A knob 110 is screwed on shaft-extension 106 and is locked in place by nut 111, the knob being actuatable to rotate pinion 105 in one direction, as will presently appear.

Pivoted to plate 108 at 112 is a pawl 113 (Figs. 13, 14 and 15) which is pressed by spring 114 in a manner positively to prevent counter-clockwise movement of pinion 105 (as viewed in all the figures in which it appears) but to allow clockwise ratcheting movement of that pinion.

Wheels 46a and 47a are supported by pinion 105 for rotation about axis A, but they are independently rotatable with respect to the pinion. They rest on washers 115 and 116, respectively, which, in turn, rest on snap-rings 117 and 118, respectively, sprung into annular grooves in the pinion teeth.

Independent actuating mechanisms 120 and 120b are provided for wheels 47a and 46a, respectively. These mechanisms are alike, so only one (120) need be described in detail. Corresponding parts of mechanism 120b are given the same reference number plus the sub-script "b."

Pivoted at 121 to bottom 101 of wheel 47a, is a gear segment 122 which is meshed with pinion 105. One end of coil spring 123 is applied to post 124 on wheel 47a and the other end of the spring is applied to segment 122 at 125, the spring acting in a manner tending to rotate the segment in a clockwise direction, as viewed in Figs. 14, 16 and 17. In Fig. 17 segment 122 is shown at the limit of its movement in that direction, as established by contact of shoulder 126 with wheel-wall 100. In this figure segment 122b is directly beneath and in the same relative position as segment 122, and therefore does not show. However, its shoulder 126b is now in contact with wall 104 of wheel 46a, which wall, as stated previously, directly underlies wall 100.

Fig. 17 indicates the position of the parts after the board has been "cleared" by withdrawal of all pegs in preparation for the scoring of a new game, though the board has not yet been "restored" or re-wound. Springs 123 and 123b are relatively unwound, but they are still sufficiently tensioned or loaded to appreciably resist counter-clockwise movement of the segments, for a pur-

pose to be made apparent. The corresponding number-indicia of series 42, 43 are in radial alignment as are also the lugs 67 and 68a, said lugs having been slightly advanced in a clockwise direction beyond starting positions B.

Pegs 85 and 86 are now inserted in the particular sockets 44a and 45a which are in line with starting marks B, and knob 110 is actuated to rotate pinion 105 in a clockwise direction, as viewed in Figs. 15 and 17; pawl 113 ratcheting to allow this movement. It has been pointed out that springs 123 and 123b are, in the condition of Fig. 17, sufficiently tensed or loaded to appreciably resist counterclockwise movement of segments 122 and 122b with relation to their associated wheels 47a and 46a. This resistance is greater than is the resistance of wheels 47a and 46a to rotation about their common axis, it following that the segments behave as though they were stationarily fixed to their respective wheels—that is, fixed against rotation about their individual axes 121 and 121b. The engaged teeth of the pinion and segments are, in effect, yieldably "locked," so when clockwise torque is applied to the pinion through knob 110, wheels 47a and 46a are simultaneously rotated in a clockwise direction until lugs 67 and 68a simultaneously engage pegs 85 and 86, respectively.

Wheels 46a and 47a and their count-indicia will now be in the positions of Figs. 14 and 12 but, while segment-pivots 121, 121b occupy the positions of Figs. 13 and 14, the two segments 120, 120b still remain with their stop-shoulders engaging walls 100, 104, respectively, and with their springs 123, 123b relatively un-wound.

With wheels 46a, 47a checked in their clockwise rotation by the described lug-and-peg engagement, continued clockwise rotation of pinion 105 simultaneously rotates segments 122, 122b counterclockwise (Fig. 17) about their pivots 121, 121b, respectively, until their respective end-teeth 127, 127b engage walls 100 and 104, respectively. This rotation of the segments winds springs 123, 123b; pawl 113 preventing reverse rotation of the segments when manual pressure is relieved from knob 110.

The device is now in the condition in Figs. 13 and 14 and is fully "restored," that is, it is in readiness for the scoring of a new game. From this point on, the manipulation of the pegs is, in principle, exactly like that described in connection with the embodiment of Figs. 1 through 11. However, in order to make the operation of the spring-drive clear, I will describe one scoring sequence.

Assume that in the first hand the first player, using the socket-series 42 and pegs 85, 87 for his score, makes twenty-six points. He inserts peg 87 in the socket indicating such a count (see Fig. 12). Assume the second player makes two points. He places peg 88 in the corresponding socket of series 43 (see Fig. 12).

Upon completing the next hand, the first player removes rearward peg 85 from the starting socket 44a, thus clearing that peg from the path of lug 67. Thereupon spring 123b causes segment 122b to planetate in a clockwise direction about the stationary pinion 105, carrying wheel 46a with it. Wheel 46a is thus rotated in a clockwise direction until its lug 67 engages peg 87, whereupon the wheel comes to rest with its zero mark opposite said peg (Fig. 16) thus enabling the player to insert the withdrawn peg 85 in the socket having the number corresponding to the individual count of the last hand.

Similarly, when the second player withdraws peg 86 from socket 45a, spring 123 planetates segment 122 about pinion 105, the segment thus rotating wheel 47a in a clockwise direction until lug 68a engages peg 88, bringing the wheel to rest with its zero mark opposite said peg (Fig. 16). The player then inserts peg 86 in the socket having the number corresponding to the individual count of the last hand.

The alternate advancing of the two pegs of each player and the automatic "follow-up" of wheels 46a, 47a continue until one player "pegs-out" at the winning score, all as described in connection with the embodiment of Fig. 1.

Though this is not limitative, the extent of planetary movement of segments 122, 122b under the power of springs 123, 123b, is sufficient to cause slightly more than two complete revolutions of wheels 46a, 47a. With sixty sockets in a series, this enables the scoring of a 120-point game such as cribbage, the win being indicated when one player's advanced peg reaches or passes the starting marks B for the second time. The "overrun" beyond two complete revolutions allows the device to reach the "cleared" condition of Fig. 17 when, after completion of a game-score, all pegs are withdrawn from the board.

All the reservations made in connection with the embodiments of Figs. 1 to 11, as to additional markings for intermediate total scores, etc. are to be considered as applied to the embodiment of Figs. 12 to 17.

While I have shown and described preferred embodiments of my invention, it will be understood various changes in design and arrangement may be made without departing from the spirit and scope of the invention and the broader claims appended hereto.

I claim:

1. In a game scorer, the combination of a peg board provided with an arcuately arranged series of scoring sockets adapted selectively to take a pair of scoring pegs which are to be alternately advanced beyond one another through the socket-series, an advance-counter bearing an arcuately arranged series of numbers of progressively increasing value, said counter being mounted for rotation with respect to the board and arranged with its number series concentric with the socket-series, all in a manner whereby, during counter rotation, the number series traverses the socket-series, and means for rotating said counter and comprising a gear member operatively connected to said counter, a second gear member meshed with the first mentioned gear and mounted for rotation with respect to the board, and a spring applied to said second gear member and adapted, when loaded, to rotate said second gear member and thereby to rotate the first mentioned gear and said counter in one direction; and an arresting formation on said counter and adapted to be engaged by one of the scoring pegs whereby rotation of said counter in said one direction is selectively limited.

2. In a game scorer, the combination of a peg board provided with an arcuately arranged series of scoring sockets adapted selectively to take a pair of scoring pegs which are to be alternately advanced beyond one another through the socket-series, an advance-counter bearing an arcuately arranged series of numbers of progressively increasing value, said counter being mounted for rotation with respect to the board and arranged with its number series concentric with the socket-series, all in a manner whereby, during counter

rotation, the number series traverses the socket-series, a gear member operatively connected to said counter, a second gear member meshed with the first mentioned gear and mounted for rotation with respect to the board, a spring applied to said second gear member and adapted, when loaded, to rotate said second gear member and thereby to rotate the first mentioned gear and said counter in one direction, a peg adapted to be placed selectively in said scoring sockets, and a formation on said counter and adapted to be engaged by said peg whereby the rotation of said counter in said one direction is selectively limited.

3. In a game scorer, the combination of a peg board provided with an arcuately arranged series of scoring sockets adapted selectively to take a pair of scoring pegs which are to be alternately advanced beyond one another through the socket-series, an advance-counter bearing an arcuately arranged series of numbers of progressively increasing value, said counter being mounted for rotation with respect to the board and arranged with its number series concentric with the socket-series, all in a manner whereby, during counter rotation, the number series traverses the socket-series, and means for rotating said counter and comprising a gear member operatively connected to said counter, a second gear member meshed with the first mentioned gear and mounted for rotation with respect to the board, a spring applied to said second gear member and adapted, when loaded, to rotate said second gear member and thereby to rotate the first mentioned gear and said counter in one direction, an arresting formation on said counter and adapted to be engaged by one of the scoring pegs whereby rotation of said counter in said one direction is selectively limited, and means for loading said spring and rotating said counter in the opposite direction and embodying a member applied to said second gear member and manually movable in a manner to rotate said second gear member in the opposite direction.

4. In a game scorer, the combination of a peg board provided with an arcuate series of scoring sockets adapted selectively to take a pair of scoring pegs which are to be alternately advanced one beyond the other through the socket series, an advance counter bearing an arcuate series of count-indicia, said counter being rotatably associated with the board in a manner whereby, during counter rotation, the count indicia traverse the scoring sockets, and means for rotating said counter and comprising a gear member mounted for rotation with respect to said board, a second gear member meshed with the first gear member and mounted for rotation on said counter, spring means applied to the second gear member and tending to rotate it in one direction, and ratchet means holding the first mentioned gear member against rotation in the direction in which it has a tendency to be driven by the spring-loading of the second gear member, all in a manner whereby, when the second gear member is spring loaded, said second gear member has a tendency to planetate in one direction about the first mentioned gear member and thus to rotate the counter in the last mentioned direction; and an arresting formation on said counter and adapted to be engaged by one of the scoring pegs whereby rotation of said counter in said one direction is selectively limited.

5. In a game scorer, the combination of a peg board provided with an arcuate series of scoring sockets adapted selectively to take a pair of scor-

ing pegs which are to be alternately advanced one beyond the other through the socket series, an advance counter bearing an arcuate series of count-indicia, said counter being rotatably associated with the board in a manner whereby, during counter rotation, the count indicia traverse the scoring sockets, and means for rotating said counter and comprising a gear member mounted for rotation with respect to said board, a second gear member meshed with the first gear member and mounted for rotation on said counter, spring means applied to the second gear member and tending to rotate it in one direction, ratchet means holding the first mentioned gear member against rotation in the direction in which it has a tendency to be driven by the spring-loading of the second gear member, all in a manner whereby, when the second gear member is spring loaded, said second gear member has a tendency to planetate in one direction about the first mentioned gear member and thus to rotate the counter in the last mentioned direction, an arresting formation on said counter and adapted to be engaged by one of the scoring pegs whereby rotation of said counter in said one direction is selectively limited and means for winding said spring means and comprising a member applied to said first mentioned gear member and manually movable in a manner to rotate said first mentioned gear member.

6. In a game scorer, the combination of a peg board provided with an arcuate series of scoring sockets adapted selectively to take a pair of scoring pegs which are to be alternately advanced one beyond the other through the socket series, an advance counter bearing an arcuate series of count-indicia, said counter being rotatably associated with the board in a manner whereby, during counter rotation, the count indicia traverse the scoring sockets, and means for rotating said counter and comprising a gear member mounted for rotation with respect to said board, a second gear member meshed with the first gear member and mounted for rotation on said counter, spring means applied to the second gear member and tending to rotate it in one direction, ratchet means holding the first mentioned gear member against rotation in the direction in which it has a tendency to be driven by the spring-loading of the second gear member, all in a manner whereby, when the second gear member is spring loaded, said second gear member has a tendency to planetate in one direction about the first mentioned gear member and thus to rotate the counter in the last mentioned direction, an arresting formation on said counter and adapted to be engaged by one of the scoring pegs whereby rotation of said counter in said one direction is selectively limited, and manually actuated means for further rotating said counter in said one direction and comprising a member applied to said first mentioned gear member and manually movable in a manner to rotate said first mentioned gear member.

7. In a game scorer, the combination of a peg board provided with an arcuate series of scoring sockets adapted selectively to take a pair of scoring pegs which are to be alternately advanced one beyond the other through the socket series, an advance counter bearing an arcuate series of count-indicia, said counter being rotatably associated with the board in a manner whereby, during counter rotation, the count-indicia traverse the scoring sockets, and means for rotating said counter and comprising a gear member mounted

for rotation with respect to said board, a second gear member meshed with the first gear member and mounted for rotation on said counter, spring means applied to the second gear member and tending to rotate it in one direction, ratchet means holding the first mentioned gear member against rotation in the direction in which it has a tendency to be driven by the spring-loading of the second gear member, all in a manner whereby, when the second gear member is spring loaded, said second gear member has a tendency to planetate in one direction about the first mentioned gear member and thus to rotate the counter in the last mentioned direction, a formation on said counter and adapted to be engaged by one of the scoring pegs whereby rotation of said counter in said one direction is selectively limited, and manually actuated means effective sequentially to further rotate said counter in said one direction to a predetermined position and then to re-wind the spring and comprising a member applied to said first mentioned gear member and manually movable in a manner to rotate said first mentioned gear member.

8. In a game scorer, the combination of a peg board provided with an arcuate series of scoring sockets adapted selectively to take a pair of scoring pegs which are to be alternately advanced one beyond the other through the socket series, an advance counter bearing an arcuate series of count-indicia, said counter being rotatably associated with the board in a manner whereby, during counter rotation, the count indicia traverse the scoring sockets, and means for rotating said counter and comprising a gear member mounted for rotation with respect to said board, a second gear member meshed with the first gear member and mounted for rotation on said counter, spring means applied to the second gear member and tending to rotate it in one direction, ratchet means holding the first mentioned gear member against rotation in the direction in which it has a tendency to be driven by the spring-loading of the second gear member, all in a manner whereby, when the second gear member is spring loaded, said second gear member has a tendency to planetate in one direction about the first mentioned gear member and thus to rotate the counter in the last mentioned direction, and an arresting formation on said counter and adapted to be engaged by one of the scoring pegs whereby rotation of said counter in said one direction is selectively limited, and manually actuated means for rotating the first mentioned gear in the direction opposite that against which it is held by said ratchet means and comprising a member applied to said first mentioned gear member and manually movable in a manner to rotate said first mentioned gear member.

9. In a game scorer, the combination of a peg board provided with an arcuate series of scoring sockets adapted selectively to take a pair of scoring pegs which are to be alternately advanced one beyond the other through the socket series, an advance counter bearing an arcuate series of count-indicia, said counter being rotatably associated with the board in a manner whereby, during counter rotation, the count indicia traverse the scoring sockets, a gear member mounted for rotation with respect to said board, a second gear member meshed with the first gear member and mounted for rotation on said counter, spring means applied to the second gear member and tending to rotate it in one direction, ratchet means holding the first mentioned gear member

against rotation in the direction in which it has a tendency to be driven by the spring-loading of the second gear member, all in a manner whereby, when the second gear member is spring loaded, said second gear member has a tendency to planetate in one direction about the first mentioned gear member and thus to rotate the counter in the last mentioned direction, a peg member adapted to be taken selectively in said sockets, and a formation on said counter adapted to engage said peg member and thereby selectively limit the extent of counter rotation in said one direction.

10. In a game scorer, the combination of a peg board provided with an arcuate series of scoring sockets adapted selectively to take a pair of scoring pegs which are to be alternately advanced one beyond the other through the socket series, an advance counter bearing an arcuate series of count-indicia, said counter being rotatably associated with the board in a manner whereby, during counter rotation, the count indicia traverse the scoring sockets, and means for rotating said counter and comprising a gear member mounted for rotation with respect to said board, a second gear member meshed with the first gear member and mounted for rotation on said counter, spring means applied to the second gear member and tending to rotate it in one direction, ratchet means holding the first mentioned gear member against rotation in the direction in which it has a tendency to be driven by the spring-loading of the second gear member, all in a manner whereby, when the second gear member is spring loaded, said second gear member has a tendency to planetate in one direction about the first mentioned gear member and thus to rotate the counter in the last mentioned direction, an arresting formation on said counter and adapted to be engaged by one of the scoring pegs whereby rotation of said counter in said one direction is selectively limited, and means positively limiting the extent of rotary motion of the second mentioned gear with respect to the counter.

11. In a game scorer, the combination of a peg board provided with an arcuate series of scoring sockets adapted selectively to take a pair of scoring pegs which are to be alternately advanced one beyond the other through the socket series, an advance counter bearing an arcuate series of count-indicia, said counter being rotatably associated with the board in a manner whereby, during counter rotation, the count indicia traverse the scoring sockets, and means for rotating said counter and comprising a gear member mounted for rotation with respect to said board, a second gear member meshed with the first gear member and mounted for rotation on said counter, spring means applied to the second gear member and tending to rotate it in one direction, ratchet means holding the first mentioned gear member against rotation in the direction in which it has a tendency to be driven by the spring-loading of the second gear member, all in a manner whereby, when the second gear member is spring loaded, said second gear member has a tendency to planetate in one direction about the first mentioned gear member and thus to rotate the counter in the last mentioned direction, a formation on said counter and adapted to be engaged by one of the scoring pegs whereby rotation of said counter in said one direction is selectively limited, and common means actuatable to further rotate said counter in said one direction to a predeter-

mined position and to re-wind the spring and comprising a member applied to said first mentioned gear member and manually movable in a manner to rotate said first mentioned gear member.

12. In a game scorer, the combination of a peg board provided with an arcuate series of scoring sockets adapted selectively to take a pair of scoring pegs which are to be alternately advanced one beyond the other through the socket series, an advance counter bearing an arcuate series of count-indicia, said counter being rotatably associated with the board in a manner whereby, during counter rotation, the count indicia traverse the scoring sockets, and means for rotating said counter and comprising a gear member bodily fixed in position with respect to the board and held against rotation in at least one direction, a second gear member mounted for rotation on said counter and meshed with the first mentioned gear, spring means applied to the second gear member and tending to rotate it in a direction which tends to rotate the first gear in said one direction, all in a manner whereby the spring loading of the second gear member tends to planetate it in one direction about the first mentioned gear member and thus to rotate the counter in the last mentioned direction; and an arresting formation on said counter and adapted to be engaged by one of the scoring pegs whereby rotation of said counter in said one direction is selectively limited.

13. In a game scorer, the combination of a peg board provided with an arcuately arranged series of scoring sockets adapted selectively to take a pair of scoring pegs which are to be alternately advanced beyond one another through the socket-series, an advance-counter bearing an arcuately arranged series of numbers of progressively increasing value, said counter being mounted for rotation with respect to the board and arranged with its number series concentric with the socket-series, all in a manner whereby, during counter rotation, the number series traverses the socket-series, and means for rotating said counter and comprising a gear member carried by the counter, a second gear meshed with the first mentioned gear and mounted for rotation with respect to the board, a spring applied to one of the gear members and adapted, when loaded, to set up relative rotation between said gears and thereby to rotate said counter with respect to said board, means for loading said spring; and an arresting formation on said counter and adapted to be engaged by one of the scoring pegs whereby rotation of said counter in said one direction is selectively limited.

14. In a game scorer, the combination of a peg board provided with an arcuately arranged series of scoring sockets adapted selectively to take a pair of scoring pegs which are to be alternately advanced beyond one another through the socket-series, an advance-counter bearing an arcuately arranged series of numbers of progressively increasing value, said counter being mounted for rotation with respect to the board and arranged with its number series concentric with the socket-series, all in a manner whereby, during counter rotation, the number series traverses the socket-series, and means for rotating said counter and comprising a gear member carried by the counter, a second gear meshed with the first mentioned gear and mounted for rotation with respect to the board, a spring applied to one of the gear members and adapted, when

15

loaded, to set up relative rotation between said gears and thereby to rotate said counter with respect to board in a given direction, means for loading said spring, a peg adapted to be placed selectively in said scoring sockets, and a formation on said counter and adapted to be engaged by said peg whereby the rotation of said counter in said given direction is selectively limited.

15. In a game scorer, the combination of a peg board provided with two concentric, arcuately arranged series of scoring sockets, each series being adapted to take selectively a pair of scoring pins which are to be alternately advanced beyond one another through the respective socket series, a pair of advance counters, each bearing an arcuately arranged series of numbers of progressively increasing value, said counters being mounted for rotation with respect to the board and with their number series concentric with the socket series, all in a manner whereby, during the rotation of one counter, its number series traverses one of the socket-series, and, during rotation of the other counter, its number series traverses the other socket series, a pair of spring powered drives applied, one each, to said counters to rotate them individually and selectively when the least-advanced peg is removed from the socket of an individual socket-series, a pair of arresting formations, one on each counter and each adapted to be engaged by the more advanced peg in a socket of the associated socket-series whereby such rotation of the associated counter is selectively limited; and a spring re-wind member common to both said drives whereby the springs of the two drives are simultaneously rewound.

16. In a game scorer, the combination of a peg board provided with two concentric, arcu-

16

ately arranged series of scoring sockets, each series being adapted to take selectively a pair of scoring pins which are to be alternately advanced beyond one another through the respective socket series, a pair of advance counters, each bearing an arcuately arranged series of numbers of progressively increasing value, said counters being mounted for rotation with respect to the board and with their number series concentric with the socket series, all in a manner whereby, during the rotation of one counter, its number series traverses one of the socket-series, and, during rotation of the other counter, its number series traverses the other socket series, a pair of spring powered drives applied, one each, to said counters to rotate them individually and selectively when the least-advanced peg is removed from the socket of an individual socket-series, a pair of arresting formations, one on each counter and each adapted to be engaged by the more advanced peg in a socket of the associated socket-series whereby such rotation of the associated counter is selectively limited; and a manually operated counter-restoring member which is operative to rotate said counters simultaneously.

EDWARD E. STEVENSON.
